CORPORATION OF NEW JERSEY.

GAS-LIGHTING DEVICE.

1,327,447.

Specification of Letters Patent.

Patented Jan. 6, 1920.

Application filed May 7, 1918. Serial No. 233,018.

To all whom it may concern:

Be it known that we, TOWNSEND STITES and ELMER L. KNOEDLER, citizens of the United States, residing at Gloucester City, 5 Camden county, New Jersey, have invented a new and useful Improvement in Gas-Lighting Devices, of which the following is a full clear, and exact description, reference being had to the accompanying drawings, 10 forming part of this specification, in which—

Figure 1 is a side elevation of a gas lighting device embodying our invention.

Fig. 2 is a vertical section of the same.

Fig. 3 is a top plan view of the burner 15 cap and mantle carrier.

Fig. 4 is a side elevation showing the device applied to a Bunsen tube, before the mantle is burned and shaped, and

Fig. 5 is a similar view showing the final 20 form of the mantle.

Our invention has relation to gas-lighting devices, and is designed to provide a cheap, simple and efficient gas lighting device employing an upright mantle which can be 25 used to replace bat-wing burners. Bat-wing burners, although still in large use, are very inefficient. Their use is, however, continued, because of the fact that many persons are either unable or unwilling to incur 30 the expense of providing their burners with complete incandescent lamp equipments of the relatively expensive character heretofore on the market.

Heretofore upright mantles have always 35 been factory hardened and shaped, and when applied to a Bunsen burner have been supported from above.

Heretofore it has always been considered necessary to support upright mantles from 40 above; but we have discovered that by fastening the lower end of the limp mantle fabric to a carrier, leaving the upper end free, such limp mantles can be successfully used on upright burners allowing the shrinkage 45 during burning out and shaping to proceed in a downward direction when in place on the upright burner. We have found such a system is successful, particularly where the length of the mantle is less compared with 50 the diameter than in the ordinary upright mantle supported from above, as shown in the drawing.

In accordance with our invention, we provide a lighting device comprising a burner cap member adapted to readily fit over the 55 end of a Bunsen burner tube, and such as shown at 2 in the accompanying drawing. This cap member is provided with an internal gauze 3. 4 designates an upright limp mantle whose base is firmly secured to the 60 cap, preferably by tying with a string or cord 5. The limp mantle is preferably open at both its upper and lower ends, the upper end portion being provided with a draw string 6 in order to provide for a restricted 65 opening at the top. The upper portion of the mantle is also preferably made more inflammable than its remaining portion by treating it with some suitable material, such as collodion. When the device is applied to 70 an upright Bunsen burner and lighted at its upper portion, it will burn downwardly, thereby burning out the top portion first. Consequently this portion will not be heavy 75 enough to tip over the less strong mantle 75 body and the mantle will not tip sideways while the fabric is being burned out. This making of the upper or more inflammable portion is not essential, however, with many forms of mantles and fabrics such as 80 cotton or Ramie mantles. During the incineration or burning out of the fabric, the mantle will shrink downwardly and inwardly, if it should be tipped sideways by a draft, vibration or other cause during the 85 incineration, the mantle will shape to a globular form somewhat similar to that shown in Fig. 5, when the gas and air mixture is turned on.

In order to keep the mantle from sagging 90 during shipment some further support is desirable. For this purpose we may employ a temporary internal support such as the collapsible tube 8 which can be slipped into the mantle in its collapsed form and then 95 allowed to expand so as to hold the meshes of the fabric under some vertical tension. Unless some support of this character is provided, the mantle will be liable to collapse on itself in its package during shipment and 100 hence not harden symmetrically when the fabric is burned out. The form of the mantle after removing this internal support is approximately illustrated by Fig. 4.

The advantages of our invention result from the cheapness and simplicity of the device which for the first time provides a limp upright mantle as an article of manufacture and sale, and also for the first time a limp upright mantle supported from its lower part and adapted to be attached to an upright burner.

We claim:

- 10 1. As a new article of manufacture, an upright mantle formed of textile fabric and secured at its lower end to a carrier shaped to be supported on an upright Bunsen burner, substantially as described.
- 15 2. As a new article of manufacture, a tubular mantle composed of a fabric impregnated with a refractory compound, said mantle being secured at its base to a carrier device and arranged to shrink downwardly during incineration and shaping, and being adapted to fit on an upright Bunsen burner, substantially as described.
- 20 3. As a new article of manufacture, a tubular mantle for upright Bunsen burners composed of a fabric impregnated with refractory salts of rare earths, said mantle being secured at its base to a carrier device, said carrier device forming the sole support for the mantle during incineration and shaping, and being adapted to fit on an upright Bunsen burner, substantially as described.
- 25 4. As a new article of manufacture, a tubular mantle composed of a fabric impregnated with refractory salts of rare earths, said mantle being proportioned to shape properly when incinerated in upright position and having its base portion secured to a carrier device, said carrier device forming the sole support for the mantle during incineration and shaping, substantially as described.
- 30 5. As a new article of manufacture, a tubular mantle for upright burners composed of a fabric impregnated with refractory salts of rare earths, said mantle being secured at its lower portion to a carrier device and being free at its upper end whereby it may shrink downwardly while shaping in place on an upright burner, substantially as described.
- 35 6. As a new article of manufacture, a tubular mantle for upright burners, composed of a fabric impregnated with refractory salts of rare earths, said mantle being secured at its base to a carrier device, said carrier device forming the sole support for the mantle during incineration and shaping, and also the sole means for attaching the article to an upright Bunsen burner, substantially as described.
- 40 7. As a new article of manufacture, a tubular mantle for upright burners, composed of a fabric impregnated with refractory salts of rare earths, said mantle being

secured at its base to a carrier device, said 65 carrier device forming the sole support for the mantle during incineration and shaping, and being adapted to fit on an upright Bunsen burner, the mantle being arranged to provide a restricted opening at its upper 70 end after shaping, substantially as described.

8. The combination with an upright Bunsen burner, of a tubular mantle composed of a fabric impregnated with refractory salts of rare earths, said mantle being secured at its base to a carrier device which forms the sole support for the mantle during incineration and shaping and fits on an upright Bunsen burner, substantially as described.

9. As a new article of manufacture, a tubular mantle for upright burners composed of a fabric impregnated with refractory salts of rare earths, said mantle being 85 secured at its base to a carrier device, said carrier device forming the sole support for the mantle during incineration and shaping, and being adapted to fit on the upper end of an upright Bunsen burner, and a support 90 arranged to prevent injurious distortion of the mantle during shipment, substantially as described.

10. As a new article of manufacture, a tubular mantle for upright burners, composed of a fabric impregnated with refractory salts of rare earths, said mantle being secured at its base to a carrier device, said carrier device forming the sole support for the mantle during incineration and shaping, 100 and being adapted to fit on the upper end of an upright burner, the upper portion of the mantle being more inflammable than its lower portion, substantially as described.

11. As a new article of manufacture, a 105 tubular mantle for upright burners, composed of a fabric impregnated with refractory salts of rare earths, said mantle being secured at its base to a carrier device, said carrier device forming the sole support for the mantle during incineration and shaping, 110 and adapted to slide frictionally on the upper end of a Bunsen burner, substantially as described.

12. As a new article of manufacture, a 115 tubular mantle composed of a fabric impregnated with refractory salts of rare earths, said mantle being secured at its base to a carrier device having an impedance therein, said carrier device forming the sole 120 support of the mantle during incineration and shaping and being arranged to engage the upper end of an upright Bunsen burner, substantially as described.

13. A gas-lighting device comprising a 125 cap member adapted to fit a Bunsen tube, and a limp mantle secured at its base to said cap member, said mantle having means for

providing a restricted opening at its upper end, substantially as described.

14. A gas-lighting device comprising a carrier, a mantle secured at its lower end to the carrier, and an internal temporary support frictionally engaging the upper portion of the mantle and holding the fabric

thereof in tension; substantially as described.

In testimony whereof, we have hereunto 10 set our hands.

TOWNSEND STITES.
ELMER L. KNOEDLER.
